H. W. KRAM

SEWING MACHINE

Filed Feb. 2, 1923

Patented Jan. 13, 1925.

UNITED STATES PATENT OFFICE.

HARRY W. KRAM, OF ST. LOUIS, MISSOURI, ASSIGNOR TO AMERICAN SHOE MACHINERY & TOOL COMPANY, OF ST. LOUIS, MISSOURI.

SEWING MACHINE.

Application filed February 2, 1923. Serial No. 616,586.

To all whom it may concern:

Be it known that I, HARRY W. KRAM, a citizen of the United States, and a resident of the city of St. Louis, and State of Missouri, have invented a new and useful Improvement in Sewing Machines, of which the following is a specification.

This invention relates principally to sewing machines of the waxed-thread type employing a needle-feed mechanism having a needle operating in front of a bobbin case which is removably mounted in a rotary shuttle.

The principal object of the present invention is to provide for the ready insertion or removal of the bobbin case without dismounting the needle. Other objects are simplicity of construction, cheapness of manufacture and compactness of design.

The invention consists principally in providing the needle-feed mechanism with means for shifting the needle clear of the bobbin case to permit removal and replacement of said bobbin case; and it also consists in the combinations and arrangements of parts hereinafter described and claimed.

In the accompanying drawing, wherein like numerals refer to like parts wherever they occur,

Fig. 1 is a front view of a portion of a sewing machine provided with a needle-shifting mechanism embodying my invention;

Fig. 2 is a similar view showing the positions of the parts after the throw-out arm has been actuated to move the needle to a position that will permit withdrawal and replacement of the bobbin case.

Fig. 3 is a horizontal section on the line 3—3 in Fig. 1; and

Fig. 4 is a vertical section on the line 4—4 in Fig. 1.

Referring to the accompanying drawing, my invention is shown in connection with the needle feed mechanism of a waxed-thread sewing machine comprising a shuttle-head 4, a needle-plate or work-support 5 and a bobbin-case 6 removably mounted in a rotary shuttle 7. This mechanism is well-known and it is considered unnecessary to illustrate it in detail.

Mounted on the front of the machine, below the shuttle-head 4, is a horizontally reciprocative feed-slide 8 which slidably supports a vertically reciprocative needle-bar 9.

Mounted on the upper end of needle-bar 9, opposite the bobbin-case 6, is a hooked needle 10. The needle-bar 9 is mounted in vertically alined bearings 11 that project from the top and bottom of the feed-slide 8 and is reciprocated vertically, to cause the needle 10 supported thereby to enter and withdraw from the work, by means of a horizontal rock-arm 12. This rock-arm is adapted to be swung vertically in any desired manner (not shown) and has a suitable block-and-pin connection at its free end with the lower end portion of said needle-bar. The rear face of the feed-slide 8 is formed with a horizontally extending undercut rib 13 that fits within a horizontally extending undercut slideway 14 formed in a lateral extension 15 of the shuttle-head 4. The feed-slide 8 is reciprocated horizontally, to cause the needle supported thereon to feed the work, by means of a suitable needle-feed mechanism comprising a feed-segment 16 supported on the forward end of a rock-shaft 17, which is journaled in a horizontal bearing 18 at one side of the shuttle-head 8 and is adapted to be actuated in any desired manner (not shown). The feed-segment 16 is provided in its front face with an arcuate slideway 19 adapted to receive a slideblock 20 mounted on one end of a link 21, whose opposite end is pivotally secured by means of a cap screw 22 to a crank-arm 23 that projects radially from the rear end of a rock-shaft 24 journaled in a horizontal bearing 25 formed in the feed-slide 8. The arcuate slideway 19 is described around the axis of the rock-shaft 24 as a center and is provided at its upper and lower ends with stop-pins 19^a which serve to retain the slide-block 20 within said arcuate slideway. The rock-shaft 24 is disposed parallel with the rock-shaft 17 which supports the feed-segment 16 and is provided with an axial bore, within which is slidably mounted a plunger 26 whose rear end portion is adapted to extend into a hole provided therefor in the link 21 that connects the radial arm 23 of said rock-shaft 24 with said feed-segment 16.

Sleeved on the plunger 26 is a coiled spring 27 whose rear end abuts against a shoulder on said plunger and whose forward end abuts against a shoulder formed in the forward end portion of the bore in the rock-shaft 24. This spring serves to normally hold the spring-pressed plunger 26 with

its rear end portion entered within the hole in the connecting link 21 whereby said link and the feed-slide are normally rigid relative to each other. By this arrangement 5 the oscillatory movement of the feed-segment 16 imparts a horizontal reciprocative movement to the feed-slide, whereby the needle carried thereby is adapted to feed the work.

- 10 The forward end of the spring-pressed plunger 26 is provided with a knob 28, whereby said plunger may be withdrawn from the hole in the link 21. A throw-out arm 29 extends horizontally across the front 15 face of the feed-slide and has one end keyed or otherwise rigidly secured to the forward end of the rock-shaft 24 between the knob or handle 28 of the spring-pressed plunger 26 and the bearing for said rock-shaft. 20 Movement of the operating arm 29 longitudinally of the rock-shaft 24 is prevented by means of a clamping screw 29^a, which engages the split hub portion of said arm. The free end of the throw-out lever 29 is 25 provided with a spring-pressed latch-pin 30 adapted to enter within any of a series of holes 31 formed in the adjacent front face of the feed-slide, which holes are arranged on an arc of a circle described around the pivotal axis of the throw-out lever. By this arrangement, the engagement of the latch-pin 30 with any one of the series of holes 31 in the feed-slide serves 30 to lock the throw-out arm 29 and the connecting link 21 in the desired angular positions.

The spring-pressed latch-pin 30 at the free end of the throw-out lever is preferably provided with a handle or knob 32, whereby said pin may be readily withdrawn from one of the slots 31 and the throw-out lever swung to a position that will cause said latch-pin to engage a different hole. This change in the angular position of the 45 throw-out lever lengthens or shortens the horizontal movement of the feed-slide, whereby the length of stitch may be varied.

When it is desired to remove the bobbin case, the spring-pressed plunger 26 and the 50 spring-pressed latch-pin 30 are withdrawn from the holes engaged thereby in the link 21 and the feed-slide 8, respectively. The throw-out arm is then swung anti-clockwise as far as possible, which action rotates the 55 rock-shaft 24 and causes the crank-arm 23 thereof to carry with it the end of the connecting link 21. During this movement the entire feed-slide is forced to move to the left a distance that is twice the throw of the crank-arm 23, which movement is sufficient to shift the needle carried by said feed-slide to one side of the bobbin case and thereby permit said bobbin case to be withdrawn from the shuttlehead. After the 60 bobbin case is replaced, the throw-out arm

is turned to its normal position, during which time the spring-pressed plunger 26 and the spring-pressed latch-pin 30 enter into the holes provided therefor in the link 21 and feed-slide 8, thereby locking said link and said operating arm in their positions. 70

It is obvious that numerous changes may be made without departing from the invention, and I do not wish to be limited to the 75 precise construction shown and described.

What I claim is:

1. A sewing machine comprising a removably mounted bobbin case, a horizontally reciprocative needle operating in front of said bobbin case, means for imparting such movement, and means associated with said needle actuating means for shifting said needle to one side of said bobbin case to permit removal and replacement of 80 the latter. 85

2. A sewing machine comprising a removably mounted bobbin case, a horizontally reciprocative feed-slide having a normally limited stroke, means normally connected with said feed-slide for actuating the same, a needle mounted on said feed-slide and operating in front of said bobbin case, and means for disconnecting said feed-slide from the actuating means therefor, whereby said feed-slide is adapted to be moved a distance sufficient to shift the needle thereon to one side of said bobbin case. 90 95

3. A sewing machine comprising a removably supported bobbin case, a horizontally reciprocative feed-slide having a needle operating in front of said bobbin case, a rock-shaft journaled in said feed-slide and having a crank-arm, a horizontally reciprocative link having a pivotal connection with said crank-arm, means normally engaged with said link for preventing swinging movement of said link with relation to said crank-arm, means on said rock-shaft normally engaged with said feed-slide for preventing the rocking movement of said rock-shaft, and means for disengaging said link 100 105 110 115 120 125 130

engaging means and said feed-slide engaging means from said link and said feed slide, respectively, whereby said rock-shaft is adapted to be actuated to lengthen the stroke of said feed-slide. 4. A sewing machine comprising a removably supported bobbin case, a horizontally reciprocative feed-slide carrying a needle operating in front of said bobbin case, a rock-shaft journaled in said feed-slide and having a crank-arm, a horizontally reciprocative link having one end pivotally connected to said crank-arm, a spring-pressed plunger axially disposed within said rock-shaft and adapted to normally engage said link to prevent relative swinging movement of said link and said crank-arm, an operating arm fixed to said rock-shaft, a spring- 120 125 130

pressed latch-pin mounted on said operating arm and adapted to normally engage said feed-slide to hold said arm in position and to prevent rocking movement of said rock-shaft, said plunger and said latch-pin being adapted to be disengaged from said link and said feed-slide, respectively, whereby said operating arm is adapted to be actuated to rock the rock-shaft and thereby lengthen the 10 stroke of said feed-slide.

5. A sewing machine comprising a removably supported bobbin case and a horizontally reciprocative feed-slide carrying a needle operating in front of said bobbin case, a rock-shaft journaled on a horizontal axis in said feed-slide and having a crank-arm, a horizontally reciprocative link pivotally connected at one end to said crank-arm, and an oscillatory feed-segment operatively engaging the other end of said link to 15

reciprocate the same, a spring-pressed plunger axially disposed within said rock-shaft and adapted to normally engage a hole in said link to prevent relative swinging movement of said link and said crank-arm, 25 an operating arm fixed to said rock-shaft, a spring-pressed latch-pin on said arm and adapted to normally engage a hole in said feed-slide to prevent swinging movement of said operating arm and rocking movement 30 of said rock-shaft, and knobs on the forward ends of said plunger and said latch-pin to permit said members to be disengaged from said link and said feed-slide, whereby said arm is adapted to be actuated to rock said 35 rock-shaft and thereby lengthen the stroke of the feed-slide.

Signed at St. Louis, Missouri, this 31st day of January, 1923.

HARRY W. KRAG.
